UNITED STATES PATENT OFFICE.

EMMA D. JONES, OF COOKSVILLE, ILLINOIS.

ENVELOPE.

Application filed December 8, 1925. Serial No. 72,981.

The present invention relates to envelopes, and aims to provide an envelope having novel and improved sealing means in order that the envelope can not be opened or the 5 contents removed without detection.

Another object is the provision of such an envelope wherein the postage stamp when applied will aid in sealing the envelope, thereby requiring the mutilation of the stamp 10 in order to open the envelope without tearing or cutting other portions of the envelope.

It is also an object of the invention to provide an envelope of the character indicated which may be composed of a single 15 blank, and which is simple and inexpensive to manufacture.

With the forgoing and other objects in view, which will be apparent as the description proceeds, the invention resides in the 20 construction and arrangement of parts, as hereinafter described and claimed, it being understood that changes can be made within the scope of what is claimed, without departing from the spirit of the invention.

25 The invention is illustrated in the accompanying drawing, wherein—

Figure 1 is a rear view of the improved envelope prior to the sealing thereof.

Fig. 2 is a front view of the envelope.

30 Fig. 3 is a longitudinal section through the seal taken on the line 3—3 of Fig. 2, with the envelope closed and sealed.

Fig. 4 is a plan view of the blank from 35 which the envelope is folded.

The envelope is formed from a single blank of suitable paper or other material. The envelope has the front or face portion 7 and the back portion composed of the flaps 8, 9 and 10 extending from the portion 7 and 40 folded back against the portion 7. The flap 9 overlaps the flap 8 and is attached thereto by the adhesive material 11 on the inner surface of the flap 9, and the end flap 10 overlaps the flaps 8 and 9 and has adhesive material 12 thereon causing the flap 10 to adhere to the flaps 8 and 9, thereby forming the body of the envelope which is open at that end opposite to the end of the portion 7 to which the flap 10 is attached. The blank has 45 gussets 13 uniting the flaps 8 and 9 with the flap 10 at the corners between them, in order to reinforce the envelope at the corresponding corners thereof. The gussets 13 are folded with the flaps 8 and 9, and with the 55 flap 10.

A closure flap 14 extends from the end of

the front portion 7 opposite to the flap 10, and has adhesive 15 on the inner surface thereof to enable the flap 14 to be attached to the flaps 8, 9 and 10 in closing the envelope. There are gussets 16 between the flap 14 and the flaps 8 and 9 at the corners between them which are folded with the flaps 8 and 9 and with the flap 14 in order to reinforce and protect the corresponding corners 60 of the envelope when the flap 14 is closed. The flap 10 is tapered and extends substantially the entire length of the envelope, while the flap 14 is also preferably tapered but is of shorter length. 65

In order to seal the envelope, the front portion 7 is provided adjacent to the open end or mouth of the envelope with the slots 17 over which the postage stamp 18 is pasted on the portion 7. As shown, the slots 17 are 70 located midway between the longitudinal edges of the envelope adjacent to the flap 14. A tongue 19 extends from the end of the flap 10 at the open end or mouth of the envelope to be folded inwardly so as to enter 75 the pocket of the envelope behind the slots 17. The flaps 8 and 9, as shown, have notches 20 at the open end or mouth of the envelope to facilitate the folding of the tongue 19 back into the envelope, and the 80 tongue 19 is provided with adhesive material 21 at that side which rests against the inner surface of the front portion 7. The tongue 19 is of a width to permit it to be inserted or threaded through the slots 17 if 85 desired.

In sealing the envelope, after the letter 22 (or other contents) is inserted into the envelope, the tongue 19 is moistened, and is 90 then folded and inserted into the envelope 95 between the letter 22 and front portion 7, so as to adhere to the inner surface of the portion 7. The adhesive material 15 of the flap 14 is then moistened and said flap 14 closed and attached to the back portion of 100 the envelope. The postage stamp 18 is then pasted on the front portion 7 over the slots 17 so as to adhere to the portion 7 around the slots, and the postage stamp will also adhere to the tongue 19 through the slots 17. 105 If desired, when inserting the tongue 19 into the envelope, the tongue may be inserted outwardly through the first slot 17 and then inwardly through the second slot, in order to thread the tongue through the slots or 110 openings.

The envelope is therefore sealed at three

points. Thus, the flap 14 is attached to the back portion of the envelope, the tongue 19 extending from the back portion is attached to the front portion across the mouth or open end of the envelope, and the postage stamp 18 is attached to the tongue 19. Consequently, in order to open the envelope and remove the letter or contents 22 without cutting or tearing the envelope, it is necessary to remove the stamp 18 from the tongue 19, to remove the flap 14 from the flaps 8, 9 and 10, and to remove the tongue 19 from the front portion 7. The stamp 18 adhering to the portion 7 and tongue 19 cannot be removed without being mutilated, so that the tampering with the stamp can be detected. Furthermore, the tongue 19 cannot be detached from the portion 7 and stamp 18 without tearing or mutilating the envelope so as to afford means of detection. Consequently, the envelope is sealed to prevent unauthorized opening of the envelope or removal of the contents without the tampering being indicated or detected. It is apparent that even though the flap 14 is loosened and opened, the contents of the envelope cannot be removed without tearing or releasing the tongue 19 which adheres both to the front portion 7 and to the postage stamp 18. 30. By the provision of the slots 17 between the longitudinal edges of the envelope, the stamp 18 will be located at a position sufficiently below the upper edge of the envelope

to enable a special delivery or other postage stamp to be applied to the face of the envelope above the stamp 18 in the upper right hand corner.

Having thus described the invention, what is claimed as new is:—

An envelope formed from a single blank and comprising a front portion having a flap extending therefrom, a back flap extending from the front portion opposite to the closure flap and other back flaps extending from the front portion between the closure flap and first named back flap, the back flaps being secured together adhesively in overlapping relation to provide the back of the envelope, the firstnamed back flap having a tongue extending therefrom adjacent to the closure flap and adapted to be folded entirely into the envelope completely behind said front portion, said front portion having an opening to expose said tongue, with the tongue entirely behind said front portion, in order that a stamp pasted on said front portion over said opening will adhere to said tongue through said opening, and the closure flap and tongue both having adhesive material on the rear surfaces thereof in order that the tongue may adhere to the rear surface of the front portion and that the closure flap may adhere to the back flaps.

In testimony whereof I hereunto affix my signature.

EMMA D. JONES.
